CLAIM

The ornamental design for a display screen with graphical user interface, as shown and described.

DESCRIPTION

FIG. 1 is a front view of a display screen with graphical user interface of our new design; and,

FIG. 2 is a front view of the display screen with graphical user interface of FIG. 1 shown with additional content shown in broken lines.

The broken line showing of the text, the remainder of the graphical user interface, and display screen and the remainder of the device containing the display screen with graphical user interface in FIG. 2 is for environmental purposes only and forms no part of the claimed design.
